UNITED STATES PATENT OFFICE.

STEPHEN E. CIBULAS, OF BRIDGEPORT, CONNECTICUT, ASSIGNOR TO THE G. DROUVE COMPANY, OF BRIDGEPORT, CONNECTICUT.

WINDOW-OPERATING DEVICE.

954,851.

Specification of Letters Patent. Patented Apr. 12, 1910.

Application filed July 17, 1909. Serial No. 508,238.

To all whom it may concern:

Be it known that I, STEPHEN E. CIBULAS, a citizen of the United States, and a resident of Bridgeport, in the county of Fair-
field and State of Connecticut, have in-
5 vented a certain new and useful Improved
Window-Operating Device, of which the
following is a specification.

My invention relates to an improvement
10 in window operating devices adapted to op-
erate a series of windows and shutters, and
particularly to that class having two parallel
operating rods located in front of the win-
dows or shutters with links and levers con-
15 necting the rods with the windows so that
the windows are actuated by the longitudi-
nal movement of the rods.

The object of my invention is to simplify
the construction by dispensing with one of
20 the rods and so arranging the intermediate
mechanism between the single operating rod
and windows that less power is required to
operate the windows than where two rods
are used, and, further, to thoroughly brace
25 the windows when closed.

To enable others to understand my in-
vention, reference is had to the accompany-
ing drawings, in which—

Figure 1 represents a front elevation of
30 two closed windows of a series adapted to
swing on a horizontal axis, and a broken
view of the building wall and operating
rod; Fig. 2 is a sectional view on line *a* *a*
of Fig. 1; Fig. 3 is an enlarged view of an
35 arm of the mechanism and window link, and
swivel connecting the arm and link; Fig. 4
is a side elevation of Fig. 3; Fig. 5 is a plan
view of the mechanism shown at Figs. 1
and 2, and the position it occupies when
40 the window is open; and Fig. 6 is an en-
larged detail view of one of the rod sup-
porting brackets, and end view of the rod.

The windows 1 and 2 (Figs. 1 and 2)
have the side pintles 1^a and 2^a pivotally
45 supported so as to swing on substantially
horizontal axis.

3 are brackets, provided (see also Fig.
6) with the usual antifriction rolls 4 for
supporting the single operating rod 5. This
50 rod carries the rack 6 at its outer end adapt-
ed to mesh with the pinion 7 on the short
shaft 8 journaled in the bracket 9. This
shaft carries the grooved pulley 10 for ac-
tuating the operating rod in the direction

of arrows *b* *c* through the medium of the 55
chain 11.

12 are arms pivotally supported by one
end to the brackets 3, while the opposite
ends actuate the window links 13 through
the medium of a compound swivel connec- 60
tion comprising (see also Fig. 4) the knee
14 which is pivoted on the screw 15 in the
end of arm 12, and the clamp 16 is swiveled
to the knee through the medium of the pin
or stud 17 projecting from said clamp, 65
which clamp is pivotally held against said
knee by the nut 18. The inner end of the
window link is pivotally attached to the
window bracket 19, while its outer end is
adjustably supported in the before men- 70
tioned clamp.

Referring to Fig. 2, 20 are links pivotally
supported to the arms 12 and the collars 21,
which collars are adjustably supported on
the operating rod. When, therefore, the 75
operating rod 5 is actuated in the direction
of arrow *b*, the mechanism will assume the
position shown at Fig. 5, with the bottom
of the window carried out, and when said
rod is moved in the direction indicated by 80
arrow *c*, the windows will be closed and the
mechanism connected therewith will assume
the position shown at Fig. 2. When the
windows are closed, the links 20 will stand
practically at right angles to the operating 85
rod 5 and thus act as a brace to effectually
resist any outward pressure brought against
the bottom of the windows. This bracing
feature will also keep the windows from
rattling. 90

The ends of the arms 12 project rear-
wardly beyond their pivotal points or screws
25, so that said projecting ends will bear on
the brackets 3 to counteract any lifting
tendency of the link mechanism when the 95
operating rod is actuated.

While I show well known mechanism for
longitudinally actuating the window operat-
ing rod, it will be understood that any other
cheap and simple device that would answer 100
the purpose could be substituted therefor.

Having thus described my invention, what
I claim is:—

In a window operating device having a
single round operating rod adapted to open 105
and close a series of horizontally arranged
windows and a series of rod supporting
brackets, of a series of arms pivotally sup-

ported on said brackets, said arms projecting rearwardly beyond their pivotal point to maintain said arms in a horizontal position, a swivel at the outer end of each arm, a window link adjustably connected to each swivel, and a series of links 20 pivotally connecting the operating rod with the arms and located intermediate of the ends of said arms so that, when the windows are closed,

10
said links will serve to maintain the windows in such closed position.

Signed at Bridgeport in the county of Fairfield and State of Connecticut this 16 day of July A. D. 1909.

STEPHEN E. CIBULAS.
